UNITED STATES PATENT OFFICE.

URASABURO TOMITA, OF NEW YORK, N. Y., ASSIGNOR TO MORIMURA BROS. INC., OF NEW YORK, N. Y., A CORPORATION OF JAPAN.

DESIGN FOR A PLATE OR SIMILAR ARTICLE.

Application filed February 10, 1928. Serial No. 25,365. Term of patent 7 years.

To all whom it may concern:

Be it known that I, URASABURO TOMITA, a subject of the Emperor of Japan, residing in the city of New York, county of Bronx, and State of New York, have invented a new, original, and ornamental Design for Plate or Similar Article, of which the following is a specification, reference being had to the accompanying drawing, forming part hereof.

The figure is a plan view of a plate, showing my new design, it being understood that the border ornamentation shown in the drawing is repeated around the circle of the plate.

I claim:

The ornamental design for a plate or similar article, as shown and described.

URASABURO TOMITA.
